CLAIM

The ornamental design for a one-piece slip, as shown and described.

DESCRIPTION

FIG. 1 is a top view of a one-piece slip, according to the new design;

FIG. 2 is a bottom view thereof;

FIG. 3 is a front side elevation view thereof, with the rear being a mirror image thereof;

FIG. 4 is a side left side elevation view thereof, with the right side being a mirror image thereof;

FIG. 5 is a top perspective view thereof; and,

FIG. 6 is a bottom perspective view thereof.

The nature and intended use of the article in which the design embodied is for the occasion of running a downhole tool into a wellbore via a workstring, and the downhole tool undergoes a setting sequence and/or disconnect from the workstring for which the slip ‘fractures’, and helps keep the tool set in place.
